AUTOMOBILE REAR VIEW MIRROR

Cornelius T. deKam, Jr., Oak Park, Mich., assignor to
Chrysler Corporation, Highland Park, Mich., a corpora-
tion of Delaware

Application May 29, 1956, Serial No. 41,697

Term of patent 14 years

(Cl. D14—6)

Fig. 1 is a side elevational view of an automobile rear view mirror showing my new design;

Fig. 2 is a plan view thereof;

Fig. 3 is a front elevational view thereof; and

Figs. 4, 5, 6 and 7 are sectional views taken on the
line 4—4, 5—5, 6—6 and 7—7, respectively, of Fig. 1.

The dominant features of my design reside in the por-
tions shown in full lines.

I claim:

The ornamental design for an automobile rear view mirror, substantially as shown and described.
